Primary Examiner—Gary D. Watson*Assistant Examiner*—Patricia Palasik(74) *Attorney, Agent, or Firm*—Goodwin Procter LLP(57) **CLAIM**

The ornamental design for a half-blind router bit depth guide, as shown and described.

DESCRIPTION

FIG. 1 is a perspective view of the half-blind router bit depth guide.

FIG. 2 is a top view thereof.

FIG. 3 is a bottom view thereof.

FIG. 4 is a front elevational view thereof.

FIG. 5 is a rear elevational view thereof.

FIG. 6 is a right side elevational view thereof; and,

FIG. 7 is a left side elevational view thereof.
